[57] CLAIM

The ornamental design for an earring, as shown and
described.

DESCRIPTION

FIG. 1 is a front elevational view of an earring showing
my new design, the rear elevational view being a mirror
image thereof;

FIG. 2 is a side elevational view taken from the right of
FIG. 1, the side opposite being a mirror image thereof;

FIG. 3 is a top plan view thereof; and

FIG. 4 is a bottom plan view thereof.

FIG. 1

FIG. 2

FIG. 3

FIG. 4
